PORTABLE STRING OF SOUND
PRODUCING DEVICES

Edwin J. Nicorvo, South Amboy, N. J.

Application June 23, 1948, Serial No. 34,676

8 Claims. (Cl. 177—7)

1

This invention relates to novel devices and more particular to audible devices which find particular use at the Christmas season. In one of its more particular aspects the invention is directed to portable strings or sets of electrically operated bells especially useful in the Christmas season, on Christmas trees, over fire places, on the outside of homes, etc., for either or both audible and visual decorative purposes and also to novel parts thereof.

Some illustrative embodiments of the invention are shown in the accompanying drawings, wherein:

Fig. 1 is an essentially diagrammatic view, with the bell and support assembly shown in section of one of the embodiments, of the invention.

Fig. 2 is a perspective view of an individual assembly of bell, support and electrical actuator.

Fig. 3 is a demountable and readily replaceable modification of the individual assembly shown in Fig. 2.

Fig. 4 is a view showing a socket and the screw base for supporting and electrically coupling thereto the demountable modification shown in Fig. 3.

Fig. 5 is an essentially diagrammatic foreshortened view showing the solenoid windings in parallel relationship to each other.

As shown in Fig. 1, there is provided a male plug or connector 10 whose housing 11 carries a pair of male contacts 12 and 13; and a female plug 14 whose housing 15 carries a pair of contacts 16 and 17. The ends of an electric conductor 18 are supported by the respective plugs 10 and 14 and are electrically connected to the respective contacts 13 and 16. Located in the plug housing 11 and having one terminal thereof electrically connected to the contact 12 is an interrupter 19 of suitable design. The ends of an electric conductor 20 are supported by the respective housings 11 and 15 and are electrically connected to the respective contacts 12 and 17. A plurality of windings 21 of individual solenoids 21 are electrically connected in series and to the conductor 17 and to the other terminal of the interrupter 19. In one of the preferential embodiments of the invention there are employed five of said solenoids only one complete one being shown in Fig. 1 and the windings of the other four however being illustrated. Each set of windings 21 is wound around a hollow cylinder support 23 having an opening therethrough. Extending through said hollow cylinder 23 is an elongated movable core 24 having a pair of stop flanges 25 and 26. Supported by the conductors which extend from the

2

termini of the individual solenoid windings 21 is a dielectric housing which is essentially a cylinder 27, a closure cap 28 secured each end thereof. Struck out of and depending from the lower cap 28 is an ear 29 having an opening therethrough. A bell 30, having a free swinging striker 31 suspended from the upper part thereof, is disposed below the ear 29 and has a loop support 32 at the central upper end thereof. A ring connector 33 extends through said loop 32 and the opening in said ear 29 so that said bell 30 and striker 31 are supported for free swinging motion. Coupled to the lower end of said movable core 24 is one end of a flexible string or wire 34 whose other end 15 is coupled to one side of the bell 30, or it may be connected directly to the striker 31. Any other type of bell as striker assembly may be used as for example the conventional spherical bell with ball striker therein generally termed a sleigh bell. 20 When such a bell is used it is simply string suspended from the core 24. A plurality of and preferable five of said assemblies as shown in Fig. 2 and a cross section of which is shown in Fig. 1 are employed, with the windings thereof 25 being in series and in a circuit such as that shown in Fig. 1.

Such a string or set of bells is portable, may be arranged on the branches of a Christmas tree or in any other desirable location. Then the plug 10 30 is grasped by one hand and the male contacts 12 and 13 may be inserted into an ordinary live female plug generally found in the base-board of a home or the like to become electrically coupled with a source of electric energy. Passage of current will take place in the circuit from said source of electric energy through contact 13 conductor 18, the windings 21, the interrupter 19 and contact 12, back to the source of energy. In the course of passage of current through the windings 40 21 of said circuit the core 24 of each of the solenoids is actuated upwardly. Upon upward movement of the core 24 there is an upward pull on the string 34 which is transmitted to the bell 30 to swing the bell about its loop 32, whereupon the 45 free swinging striker 31 of the bell 30 swings against the bell 30 to provide a musical note or ring. The interrupter 19 in the circuit serves to make and break the circuit at desired intervals and the number of makes and breaks per unit 50 of time may be controlled by the particular design of the interrupter 19.

With the type of wiring diagram shown in Fig. 1 it is possible to connect a number of strings to each other by inserting the male contacts of one 55 string into the female contacts of another string.

While the windings 21 of any string are in series they are in parallel across the main circuit. If desired, a simple two wire system may be employed with each of the windings 21 and the male and female contacts being in parallel relationship to each other. In that system, like the system shown in Fig. 1, the windings 21 are in series with the interrupter 19 and the contacts 12 and 13, but differs from the system of Fig. 1 in that the windings 21 are in parallel with each other.

It is also within the purview of this invention to provide a plurality of electric sockets 35, which as shown may be of the screw type 36. They may be substituted in the positions of the solenoid windings in the various circuits hereinbefore described. When such arrangements are employed there may be coupled with said sockets, novel devices. The novel devices consist of a solenoid assembly which may be located in a screw base 40 with one end of the winding 21 being connected to a central contact 41 of the screw base and insulated from a screw contact sleeve 42 electrically connected to the other end of winding 21. The sleeve 42 terminates in a knurled flange 43 carrying a depending loop 44, extending through the loop 32 of the bell 30. The assembly as shown in Fig. 3, may be screwed directly into the socket 36 in the same manner as in the ordinary incandescent lamp screwed into its socket.

Also if desired, the individual sockets 35 may each contain a circuit interrupter 19 and in such a case, I prefer that these sockets be arranged in parallel relationship to each other. The circuit interrupters 19 when so employed are differently timed so that the various bells are actuated to ring at different times. The interrupters 19 used in the various modifications of this invention are electrothermal responsive and are preferably of the bimetallic type which due to the rise in temperature of their bimetallic element upon the passage of current in the circuit including the solenoid windings, automatically break that circuit, and upon cooling automatically make the circuit. For my purposes, I may employ those of the well-known "Twinkle-button" type.

While the invention has been described in detail it is not to be limited thereby, because various changes and modifications may be made therein.

I claim:

1. A portable electric decorative set of bells comprising a connector having a pair of electrical contacts capable of being electrically connected to an ordinary live electric female plug in a home, a plurality of solenoid windings, a plurality of bell elements, striker elements for said bell elements, means movable upon the electrical energization of said windings, said means associated with said bell elements and striker elements for moving one of said elements relative to the other, circuit making and breaking means, each of said windings, said circuit making and breaking means and said contacts being in series, said circuit making and breaking means being automatically operable to make and break the circuit made when said contacts are electrically connected to said live female plug.

2. A portable electric decorative set of bells comprising a connector having a pair of electrical contacts capable of being electrically connected to an ordinary live electric female plug in a home, a plurality of solenoid windings, a

10 plurality of bell elements, striker elements for said bell elements, means movable upon the electrical energization of said windings, said means associated with said bell elements and striker elements for moving one of said elements relative to the other, circuit making and breaking means, said windings being in series with each other and with said contacts and said circuit making and breaking means, said circuit making and breaking means being automatically operable to make and break the circuit made when said contacts are electrically connected to said live female plug.

15 3. A portable electric decorative set of bells comprising a connector having a pair of electrical contacts capable of being electrically connected to an ordinary live electric female plug in a home, a plurality of solenoid windings in parallel with each other, a plurality of bell elements, striker elements for said bell elements, means movable upon the electrical energization of said windings, said means associated with said bell elements and striker elements for moving one of said elements relative to the other, circuit making and breaking means, each of said windings, said circuit making and breaking means and said contacts being in series, said circuit making and breaking means being automatically operable to make and break the circuit made when said contacts are electrically connected to said live female plug.

20 4. A portable electric decorative set of bells comprising a connector having a pair of electrical contacts, a plurality of solenoid windings, a plurality of bell elements, striker elements for said bell elements, means movable upon the electrical energization of said windings, said means associated with said bell elements and striker elements for moving one of said elements relative to the other and electrothermal responsive means for automatically making and breaking an electric circuit, each of said windings being in series with said electrothermal responsive means and said contacts.

25 5. A portable electric decorative set of bells comprising a male plug having a pair of electrical contacts capable of being inserted into an ordinary electric female plug in a home, a plurality of solenoid windings, a plurality of bell elements, striker elements for said bell elements, means movable upon the electrical energization of said windings, said means associated with said bell elements and striker elements for moving one of said elements relative to the other, electrothermal responsive means for automatically making and breaking an electric circuit, said electrothermal responsive means being coupled with said male plug, each of said windings being in series with said electrothermal responsive means and said contacts.

30 6. A portable electric decorative set of bells comprising a male plug having a pair of electrical contacts capable of being inserted into an ordinary electric female plug in a home, a plurality of solenoid windings parallel with each other, a plurality of bell elements, striker elements for said bell elements, means movable upon the electrical energization of said windings, said means associated with said bell elements and striker elements for moving one of said elements relative to the other, electrothermal responsive means for automatically making and breaking an electric circuit, said electrothermal responsive means being coupled with said male plug, each

of said windings being in series with said electro-
thermal responsive means and said contacts.

7. A portable electric decorative set of bells
comprising a connector having a pair of elec-
trical contacts capable of being electrically con-
nected to an ordinary live electric female plug
in a home, a plurality of solenoid windings, a
plurality of housings, said solenoid windings dis-
posed in said housings, a plurality of bell elements,
striker elements for said bell elements, means
movable upon the electrical energization of said
windings, said bell elements swingably supported
by said housings, said means operatively con-
nected to said bell elements for actuating said bell
elements upon movement of said means, circuit
making and breaking means, each of said wind-
ings being in series with said contacts and said
circuit making and breaking means, said circuit
making and breaking means being automatically
operable to make and break the circuit made
when said contacts are electrically connected to
said live female plug.

8. A portable electric decorative set of bells
comprising a connector having a pair of elec-

trical contacts, a plurality of solenoid windings,
a plurality of housings, said solenoid windings
located in said housings, a plurality of bell ele-
ments, striker elements for said bell elements,
said bell elements being swingably supported by
said housings, means movable upon the energi-
zation of said windings, said means operatively
connected to said bell elements for actuating said
bell elements upon movement of said means, and
electrothermal responsive means for automatic-
ally making and breaking an electric circuit,
each of said windings being in series with
said electrothermal responsive means and said
contacts.
